UNITED STATES PATENT OFFICE.

SAMUEL ROSENBLATT, OF NEW YORK, N. Y.

SOAP-FRAME.

SPECIFICATION forming part of Letters Patent No. 349,320, dated September 21, 1886.

Application filed June 1, 1886. Serial No. 203,712. (No model.)

To all whom it may concern:

Be it known that I, SAMUEL ROSENBLATT, of the city of New York, county and State of New York, have invented a new and Improved 5 Soap-Frame, of which the following specification is a full, clear, and exact description.

This invention relates to a frame used by soap manufacturers to cool the liquid soap so as to be converted into blocks or frames of 10 soap.

The invention has for its object to produce a light, inexpensive, and strong metallic frame that may be readily taken apart and manipulated; and it consists in the various elements 15 of improvement hereinafter more fully pointed out.

In the accompanying drawings, Figure 1 is a perspective view of my improved soap-frame. Fig. 2 is a top view of the truck. Fig. 3 is a 20 section on line $x x$, Fig. 2. Fig. 4 is an outer face view of one of the end walls; Fig. 5, an inner face view of part of one of the side walls. Fig. 6 is a top view of the soap-frame.

The letter a represents a truck provided at its 25 upper side with four grooves that are adapted for the reception of the lower edges of two metal side walls, b , and two metal end walls, c . The right and left ends of each side wall project beyond the end walls, as shown, and are reinforced by upright strips e , Fig. 5, that form shoulders against which the end walls rest, thus constituting proper joints. Each end wall, c , is secured in place by means of bars $f f'$, passing through perforations d in side 30 walls, the upper bars, f , being riveted to the end wall, while the lower bars, f' , are detached therefrom. The upper riveted bar, f , prevents the end wall, c , from tilting both inwardly and outwardly, while the other or detached bars, 35 f' , in conjunction with strips e , prevent such end wall from tilting outward only.

If the soap-frame is to be taken apart, the bars f' are first withdrawn, and then the side walls are free to be raised and removed from 40 the truck. To hold the bars $f f'$ in place, and to firmly lock all parts of the frame together, such bars have eyes formed at their ends for the reception of keys or wedges g .

$h h$ are horizontal angle irons or plates riveted to the side walls, b , and preventing outward bulging of such side walls, while at the same time constituting handles, by means of which the apparatus may be more conveniently manipulated.

In order to hold the frame tightly upon the 55 truck a , I make use of two adjustable clamping devices, which are adapted to be projected over the upper edge of walls c and the ends of truck a .

Each clamping device consists of a rod, i , 60 which is bent into hook shape at its lower end and has a screw-threaded upper end. A perforated plate, j , passed over rod i , is provided with two lugs, $k k$, projecting downward from its inner edge, and with two inwardly-bent 65 hooks, $l l$, projecting downwardly from its outer edge. These hooks are adapted to bear against side walls, c , and serve to keep the locking device in a proper upright position.

m is a perforated handle, screw-threaded to 70 engage upper part of rod i .

In use, the clamp is put in position and the handle is revolved, thereby lowering plate j until it is tightly held against upper edge of wall c . In this way all the parts of the frame 75 are properly joined. To take the entire frame apart the clamps are removed, the bars f' are withdrawn, and finally the side walls and end walls are lifted from the truck.

I claim as my invention—

1. The combination, in a soap-frame, of a 80 grooved truck, a , with side walls, b , and end walls, c , the transverse bars f , riveted to said end walls, c , and passing through openings d in the side walls, b , and secured by keys g , 85 substantially as specified.

2. The combination of truck a with end walls, c , side walls, b , and locking-bars f' , and with the rod i , handle m , and plate j , having lugs k and hooks l , substantially as specified. 90

SAML. ROSENBLATT.
